UNITED STATES PATENT OFFICE

117,704

DESIGN FOR A COMBINED AQUARIUM AND RADIO CABINET

Oliver Zenzen, Washburn, Ill.

Application September 25, 1939, Serial No. 87,383

Term of patent 7 years

To all whom it may concern:

Be it known that I, Oliver Zenzen, a citizen of the United States, residing at Washburn, in the county of Marshall and State of Illinois, have invented a new, original, and ornamental Design for a Combined Aquarium and Radio Cabinet, of which the following is a specification, reference being had to the accompanying drawing, forming part thereof.

The single view is a front perspective view of a combined aquarium and radio cabinet, showing my new design.

The rear of the combined aquarium and radio cabinet presents immediately rearwardly of the radio part thereof a space opening rearwardly of the cabinet for the reception of a music box or the like.

I claim:

The ornamental design for a combined aquarium and radio cabinet, as shown and described.

OLIVER ZENZEN.
